(57) **CLAIM**

The ornamental design for a flanged conduit cap with coupling, as shown and described.

DESCRIPTION

FIG. 1 is a front isometric view of a flanged conduit cap with coupling showing my new design;

FIG. 2 is a front elevational view of the flanged conduit cap with coupling;

FIG. 3 is a rear elevational view of the flanged conduit cap with coupling;

FIG. 4 is a left side view of the flanged conduit cap with coupling;

FIG. 5 is a right side view of the flanged conduit cap with coupling;

FIG. 6 is a top view of the flanged conduit cap with coupling;

FIG. 7 is a bottom view of the flanged conduit cap with coupling; and,

FIG. 8 is a rear isometric view of the flanged conduit cap with coupling.

1 Claim, 6 Drawing Sheets
